UNITED STATES PATENT OFFICE.

AUGUSTUS R. WOODYATT, OF GUELPH, ONTARIO, CANADA, ASSIGNOR TO
THE GUELPH CARRIAGE GOODS COMPANY, OF SAME PLACE.

MACHINE FOR BENDING AND SHAPING METAL ARTICLES.

SPECIFICATION forming part of Letters Patent No. 252,853, dated January 24, 1882.

Application filed August 20, 1881. (No model.)

To all whom it may concern:

Be it known that I, AUGUSTUS RICHARD WOODYATT, of the city of Guelph, in the county of Wellington, in the Province of Ontario, Canada, mechanic, have invented certain new and useful Improvements in Metal Shaping and Bending Machines; and I do hereby declare that the following is a full, clear, and exact description of the same.

10 This invention relates to a machine which is adapted to shape or bend metal plates, bars, &c., to regular or irregular forms, and to instantly drop each plate when so shaped into a hardening or tempering tank; and it consists 15 essentially of compressing-bars shaped and arranged to correspond and operate in conjunction with a forming-block made in the shape it is desired to form the metal to be operated upon, and having a slot through the table supporting the block corresponding with its shape, so that when the article is made in the desired 20 form it will immediately fall through the table into the tank of oil or other hardening liquid below for the purpose of hardening or tempering it.

25 While there are several modifications in the form and general construction of my improved machine, the drawings illustrate a machine embodying the principle of my invention. The 30 forming-block, it will be understood, is capable of being made of various shapes, according to the design of the article produced.

In Figure 1 the machine is shown in perspective, with the compressing-bars expanded to 35 permit the insertion of the metal plate to be operated upon, and showing adjustable plates attached to the block and compressing bars. Fig. 2 is a perspective view of the same machine with the compressing-bars drawn against the forming-block.

40 A is the main shaft of the machine, preferably supplied with a tight and loose pulley, B. The reciprocating movement of the cross-head C is derived from the rotary movement of the 45 shaft A, by a pitman-connection, as shown, the cross-head O being held in suitable guides formed by the main frame D, which is arranged to support the other parts, as shown.

E is a lever pivoted to the frame D, and ex-

tending back over the machine to the wedge-block frame F, where it is connected to the wedge-block G by the rod H. A spring, I, is arranged to support the end of the lever E, and on the bottom of the lever a sliding plate, J, is suspended, a hand-lever, K, being provided to 55 work the plate J and make it protrude, when desired, beyond the end of the lever E, overlapping the end of the cross-head C, as shown in Fig. 2. When in this position the upward movement of the cross-head C forces up that 60 end of the lever E, imparting a corresponding downward movement to the opposite end, to which the cross-head is attached. When the lever is let go of the spring L forces back the sliding plate J, and the spring I forces back 65 the lever E into its initial position.

M is a forming-block, made in any shape in which it is desired to form the article to be pressed. This block is supported on the table N, below which is placed the oil-tank O around 70 the block M and corresponding with its configuration. I cut a slot through the table of sufficient width to permit the article, when pressed against the block, to instantly drop through the table into the oil-tank below it.

P are compressing bars or arms pivoted on the table N, and connected to the T-shaped cross-head Q by links R. A spring, S, is arranged as shown, or in any other suitable manner, so as to force back the cross-head Q, and 80 through it keep the compressing-bars P open in the position shown in Fig. 1. A slot is made in the cross-head Q to permit the wedge-block G to pass through behind it. When the sliding plate J is thrown forward over the cross-head C, and the lever E thus made to tip up and throw down the wedge-block G, the compressing-bars P are thrown against the block M, and as the plate or other article to be formed has been placed in position, these bars press it 85 against the block M, causing it to assume the shape of the said block.

On reference to the drawings it will be noticed that the wedge-block G has an indentation, m, on its vertical edge. This indentation 95 permits the cross-head Q to spring back slightly, and in this manner remove the pressure of the compressing-bars upon the article

being shaped against the block M, permitting it, when thus loose, to fall through the slot in the table into the oil-tank O below.

- As I said in the former part of the specification, the mechanical details described and the general design of the machine can be altered considerably without affecting the principle of my invention. The shape of the forming-block can also be altered so as to shape the article 10 being pressed into any desired form; and I may further add that it is not necessary that the two forming-plates P should be used, as in some instances one plate will be sufficient to impart the desired form.
- 15 The adjustable plates (shown in Fig. 1) attached to the block and compressing-bars are applied to the machine when the shapes of the metal plates to be pressed vary. Their application obviates the necessity of changing the 20 block and compressing-bars.

What I claim as my invention is—

1. In a machine for shaping metal, a forming-block made in the form it is desired to produce the article and supported on a table 25 having a slot through its top around and corresponding with the shape of the block, in combination with a compressing bar or bars arranged to compress against the forming-block the metal to be shaped, and a tank containing 30 tempering-fluid placed below the table to receive the plates falling through the slot the instant they have been compressed into the required shape.

2. In a machine for forming metal, having a forming-block supported on a table with a slotted passage-way cut through its top, so as to permit the article compressed against the block to fall through the table, the compressing-bars P, pivoted on the table N and connected to the cross-head Q by the links R, in combination 40 with the wedge-shaped block G, arranged to operate the cross-head, as described, and having an indentation on its edge at a point which will permit the cross-head to spring back when the article has been compressed against the 45 forming-block, thereby releasing from the pressure of the compressing-bars the article, which will then fall through the slotted passage-way in the table into the oil-tank below.

3. In a machine for shaping metal, having a 50 compressing arm or arms operated in connection with a forming-block, a wedge-shaped block arranged to operate the compressing-bars and connected to the pivoted lever E by the rod H, in combination with the sliding plate 55 J, connected to the lever and provided with a spring, L, and hand-lever K for moving the plate J, so as to come in contact with the moving cross-head C, by which the lever E is tilted so as to impart a downward movement to the 60 block G, substantially as and for the purpose specified.

AUGUSTUS R. WOODYATT.
